UNITED STATES PATENT OFFICE.

ABRAHAM MOYER, OF KOSOMA, INDIAN TERRITORY.

BRIDGE.

SPECIFICATION forming part of Letters Patent No. 625,051, dated May 16, 1899.

Application filed June 16, 1898. Serial No. 683,556. (No model.)

To all whom it may concern:

Be it known that I, ABRAHAM MOYER, a citizen of the United States, residing at Kosoma, in the Choctaw Nation, Indian Territory, have 5 invented certain new and useful Improvements in Bridges; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

My invention relates to an improved bridge 15 especially adapted for rivers, such as are numerous in the Indian Territory and other southern parts of the United States. Except at times following a heavy rain there is but a small volume of water in these rivers and 20 that is generally hidden from sight by the sand-bars which cover the bed. Owing to rain, however, these rivers often rise very rapidly and form a wide and rapid stream of from two to four feet in depth. The effect 25 of such a rise and consequent increase in the volume of water is to cut the sand of the bottom into numerous channels, which channels are constantly changing and shifting and quickly destroy any roadway that may have 30 previously existed across the bed of the stream. By the time the water has subsided to its normal level the sand has been formed into numerous loosely-packed deep ridges and piles. The moving of teams across such a 35 bed is extremely difficult, as it is necessary to pass around or between the ridges and piles of sand, and the looseness thereof renders it impossible to carry normal loads.

The object of my invention is to provide a 40 bridge which can be easily and cheaply built across such a stream and which will form a firm, solid roadway that will not be affected by a sudden rise or by the quicksand-beds, which are numerous in these river-beds, and 45 which render the construction of bridges, if any of the ordinary methods are followed, very expensive.

In the drawings, Figure 1 is a transverse sectional view of a bridge embodying my improvements. Fig. 2 is a plan view thereof. 50 Fig. 3 is a longitudinal sectional view.

In constructing my improved bridge I first

sink in the bed of the river below the layer of sand (designated by the letter A) a series of heavy timbers B, which I will term "mud- 55 sills." On these I secure a tight floor C, which is of such width as to extend from four to six feet beyond both sides of the roadway which is constructed thereon, as will be hereinafter described. To this floor C and to the mud- 60 sills B, I secure the sills D of the roadway E. These sills D will be from twelve to twenty-four inches high, and the floor or roadway E will thereby be brought slightly above the top of the ordinary level of the sand A. 65

As pointed out above and as shown in the drawings, the lower floor C extends some distance beyond the sides of the roadway E, so that any water which may pass over the latter will not fall directly on the sand, but will 70 be carried by the floor C some distance away. The space between the sills D may be filled in with broken stone, sand, or other material.

To further to protect the foundation of the bridge in time of a rise in the river, I prefer 75 to employ an apron or deflecting-surface F. This is of such width as to extend from the top of the roadway E, over one edge of which it projects slightly, to points beyond the upper edge or upstream side of the floor C and 80 is preferably arranged at an angle of about forty-five degrees. This apron extends down in the sand A to about the level at which water stands during dry weather and extends the full length of the bridge. By this construction and arrangement of parts it will be seen that during a freshet the water will be carried up over the roadway E and that the foundation of the bridge will not be liable to be destroyed. 85

The roadway E may, if desired, be made of such width as to permit of the rails of a railway being secured thereon, besides providing a carriage or wagon way, or may be used simply to support a railroad-track. 90

What I claim is—

1. In a bridge, the combination of a series of mudsills, a floor or covering secured to said sills, a series of stringers or supplemental sills extending across said floor, and secured thereto; and a roadway supported on said stringers, substantially as set forth. 100

2. In a bridge, the combination of a series of mudsills arranged in the bed of a stream,

a tight covering secured on said sills, a supplemental structure mounted on and forming a roadway extending transversely of said mudsills, said mudsills and covering thereof 5 projecting beyond the sides of the roadway, substantially as set forth.

3. In a bridge, the combination of a floor or roadway, a relatively low support for said roadway, and an apron or inclined surface 10 extending in the direction of the flow of the stream from said roadway to the bed of the stream, substantially as set forth.

4. In a bridge of the character and for the purpose described, the combination of a roadway supported slightly above the level of the bed of the stream, an inclined apron extending from one edge of said roadway into the bed of the stream; and a supplemental floor 15 arranged below said roadway and projecting 20 beyond the opposite side of said roadway from said apron, as set forth.

5. In a bridge, the combination of a floor

or roadway, a support for said floor, an apron or inclined surface extending from the upstream side of the bridge to the bed of the stream and adapted to divert the body of the stream away from the bed adjacent to the bridge-support, substantially as set forth. 25

6. In a bridge, the combination of a floor or roadway, a support for said floor adapted 30 to rest on the bed of the stream across which the bridge extends, means arranged on the upstream side of the bridge for diverting the body of the stream from its normal bed adjacent to the bridge-support, and means on the 35 downstream side of the bridge for protecting the stream-bed from the water flowing through or over the bridge, substantially as set forth.

In testimony whereof I affix my signature in presence of two witnesses.

ABRAHAM MOYER.
